UNITED STATES PATENT OFFICE.

JACOB F. ZWIKER, OF TOLEDO, OHIO.

FORGING MECHANISM.

1,150,479.

Specification of Letters Patent. Patented Aug. 17, 1915.

Application filed June 6, 1914. Serial No. 843,420.

To all whom it may concern:

Be it known that I, JACOB F. ZWIKER, a citizen of the United States, and a resident of Toledo, in the county of Lucas and State 5 of Ohio, have invented a certain new and useful Forging Mechanism; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to hot metal working machinery, and particularly to forging machines, but is not restricted to such use as it, or the different features thereof, may be used in any connection for which they 20 may be adapted or appropriate.

The primary object of my invention is to improve on machines of this character, whereby to render the same more elastic in use, that is, capable of successful use on a 25 greater variety of articles than has heretofore been possible, and to enhance the practicability and commercial value of such machines.

Further objects of my invention are the 30 provision of means for ejecting a forged article from the respective dies upon a retraction of such dies; the provision of means for effecting a positive separation of the dies should the form of the forged article tend to 35 cause the dies to stick thereto, and the provision of means for automatically cleaning metal scales or other loose matter from the space between the dies when the dies are separated.

40 Further objects and advantages of the invention will be apparent from the following detailed description thereof.

The invention is fully described in the following specification, and while, in its 45 broader aspect, it is capable of embodiment in numerous forms, a preferred embodiment thereof is illustrated in the accompanying drawings, in which,—

Figure 1 is a top plan view of a machine 50 embodying the invention. Fig. 2 is a ver-

tical section thereof on the line x, x in Fig. 1. Fig. 3 is a side elevation of a portion of the mechanism employed for ejecting a forged article from one of the dies. Figs. 4, 5 and 6 are similar sectional views illustrating different stages in the forging process. Fig. 7 is a sectional detail of a positively acting die retracting means. Fig. 8 is a sectional view of a die set in article forming position with the movable die at 60 the limit of its inward stroke, a positive die retracting means and a cleaning means being associated with the die set, and Fig. 9 is a top view thereof.

Referring to the drawings, 1 designates a 65 machine frame of any suitable or convenient construction in one end portion of which is mounted a transversely movable die-block 2, which has its movement guided by a suitable guide-way 3 in the frame. The die-block 2 is intended to have movements transversely across an opening 4 provided in the frame longitudinally thereof, which opening registers at its inner end with a slide-way 5 in which a slide or cross-head 6 is 70 mounted for reciprocatory movements longitudinally of the frame. The slide or cross-head 6 carries a plunger head or ram 7 at its forward end for coacting with a movable die member of the die-block 2 when in one 75 position of the movement of such block to impart article shaping movements to such die member, as hereinafter fully described. The slide 6 has movements imparted thereto from a crank-shaft 8 to which it is connected 80 by a connecting-rod 9.

The means illustrated, in the present instance, for imparting the requisite reciprocatory movements to the die-block 2 consists in mounting a cam-slide 10 for reciprocatory 85 movements longitudinally of the frame, and providing such cam-slide, and an outwardly extending shank 2a on the die-block, with interengaging cam portions, which coact to impart reciprocatory movements to the 90 die-block when the cam-slide is reciprocated. The cam-slide 10 has connections through a connecting-rod 11 with an eccentric on the crank-shaft 8. It is to be understood that 95 no claim is made for the means described 100

for actuating the article shaping movements of the movable die member, or for the means shown and described for controlling the respective movements of the die-block, as 5 numerous means may be employed for performing such respective functions without departing from the spirit of the invention.

The die-block 2 is provided at the end thereof, which is adjacent to the frame 10 opening 4, with a fixed die member 12, having an article shaping cavity 13 therein, and with a movable die member 14, which latter is mounted for movements transversely of the die-block 2 and longitudinally of the 15 frame 1 toward and away from the die member 12, and has its article shaping surfaces of suitable form to coöperate with the cavity 13 of the member 12 to shape an article therebetween, as is well understood in 20 the art. The die member 14, in the present instance, is the male member of the set, and is adapted to project into the cavity 13 during the shaping operation. The die member 14 is mounted and suitably guided for sliding 25 movement in a guide-way 15 provided in the die-block 2, and has a stud 16 projecting therefrom and into a registering slot 17 in the die-block, said stud and the outer end wall of the slot coöoperating to limit the 30 outward or opening movements of the movable die member relative to the fixed die member. One or more coiled compression-springs 18 are mounted between the die members 12 and 14 to normally maintain 35 such die members in spaced or retracted relation. The ends of these springs are mounted in registering sockets in the respective die members.

The outer side of the die member 12 is in 40 sliding contact with a shear-plate 19, which is fixed to the frame 1 and projects across the frame opening 4 in advance of such die member. When the die-block 2 is at the limit of its outward movement a restricted 45 opening 13^a from the inner end of the die cavity 13, axially thereof in the present instance, registers with a stock feed opening 20 in the shear-plate 19 to permit a stock-bar *a* to be projected through said openings 50 and against a combined stock-gage and ejector part 22 in the movable die member 14. Upon an inward movement of the die-block 2 to place the die members in article shaping position, the adjacent end walls of the 55 openings 13^a and 20 in the die member 12 and plate 19 have shearing coaction, thus effecting a cutting off of the heated end portion of the bar *a*, which is disposed intermediate the shear-plate 19 and gage-part 22. 60 When the die members have been moved by the block 2 to operative article shaping position the outer or free ends of such members, with respect to the die-block 2, are shown, in the present instance, as working

into a registering socket or recessed portion 65 23 in the forward end portion of the slide-way 5 of the frame.

The gage and ejector part 22 is provided with a conical head portion, as shown, which fits into a complementary conical socket in 70 the shaping face of the die member 14 and has a stem 22^a projecting rearwardly through a portion of the die member and into a spring receiving socket or chamber 75 24 in the rear portion of the movable die member, as shown in Figs. 4, 5 and 6. A coiled compression spring 25 is disposed within the socket 24 and has its outer end-thrust against a removable plug 26 in the outer end of such socket, and its inner end-thrust against a nut or shoulder 22^b on the adjacent end of the stem 22^a thereby tending to normally force the stem and its head 22 forward to the position shown in Fig. 4. The nut or shoulder 22^b, in addition to receiving the end thrust of the spring 25, 80 serves to limit the forward or ejecting movements of the part 22. When the die member 14 is moved forward to coöperate with the member 12 to shape an article the pressure 90 of the stock section *b* thereagainst causes a rearward movement of the part 22 against the tension of the spring 25 and a consequent close seating of the head thereof within the registering conical recess of the die 95 member.

Mounted in the shear-plate 19 for movements transversely thereof is an ejector-part 27 for the die member 12, said ejector part being positioned to axially register with the opening 13^a in the die member 12 when such member is in article shaping position. The ejector part 27 is provided with a conical head which normally seats in a complementary recess in the rear side of the plate 19 105 with its outer face flush with the rear side of said plate, as shown in Figs. 4, 5 and 6. The stem portion of the ejector 27 projects forward through the plate 19 into the frame opening 4 and carries a coiled compression 110 spring 28, which has one end-thrust against the outer side of the plate 19 and its opposite end-thrust against a collar on the ejector stem, as shown, whereby to urge the ejector part to have a forward or seating movement relative to the plate 19. 115

The outer end of the ejector part 27 is pivotally connected to an upright lever 29, which lever is fulcrumed at its lower end to a pair of links 30, which are pivotally 120 anchored to a stud 31 secured to the bottom wall of the opening 4. The upper end of the lever 29 is connected by a rearwardly extending rod 32 to one end of a horizontally-disposed lever 33, which extends transversely of the machine frame and is fulcrumed at its outer end to such frame, as at 125 34 (Fig. 1). The lever 33 is connected in-

termidate its ends by a ring member 35 to a slide-bar 36, which is guided for movements longitudinally of the frame by a guide part 37 fixed to the top of the frame, as shown in Figs. 1 and 3. The rear end of the slide-bar 36 carries a pivoted catch-finger 38, which, upon a rearward movement of the slide 6 from its forward position is engaged by a part 39 projecting from the slide 6, the catch-finger being moved rearward a predetermined distance with said part. When the catch-finger 38 has been moved rearward a predetermined extent by the part 39, the finger is released from engagement with the part by reason of a boss 40, which is fixed to the frame 1 and stands in the path of movement of the finger, co-acting with the registering tapered nose portion of the finger and imparting an upward or releasing movement to the finger with respect to the part 39. It is thus evident that a rearward or ejecting movement is imparted to the ejector part 27 at each rearward stroke of the slide 6. A coiled contractile spring 41 connects the upper end portion of the lever 29 to a fixed part of the frame, as for instance, a finger 42 fixedly projecting from the front end portion of the frame, said spring coöperating with the spring 28 to normally retain the ejector 27 and connected operating parts retracted to normal position.

It is evident that upon a relative retracting of the die members 12 and 14, the ejector part 22 will be moved forward relative to its die member under the influence of the spring 25, and the ejector part 27 will be moved rearward relative to its die member, effecting a release of the formed article *c* from each die member, the article then falling by gravity from between the die members through a registering subjacent discharge opening 43 into a receiving chamber 44 in the lower portion of the frame 1, as shown in Fig. 2.

It may happen in the shaping of some forms of articles that the articles will tend to resist a relative opening of the die members and that the retracting spring or springs 18 will not be of sufficient strength to overcome such resistance. In such case the head 7 of the plunger or slide 6 may have a dog 45 pivoted to the top thereof and extending forwardly therefrom with its free end provided with a lip 46 for engaging within a recess 47 in the top surface of the movable die member 14 when the plunger head is in contact with the die member, as shown in Figs. 7, 8 and 9, whereby a retracting of the plunger-head from the limit of its forward movement will cause the lip 46 to coact with the rear end wall of the recess 47 and effecting a positive starting of the rearward movement of the movable die

member. When the dog 45 has moved rearward a short distance a tapered lip or flange 48 on one side of the free end portion of the dog coacts with and rides up a registering incline 49, which is formed on an adjacent fixed portion of the machine, as for instance, on the part 50 forming the top wall of the recess 23. It is evident that the lip 46 of the dog is permitted to engage within the die member recess 47 only when such member is at or near the limit of its forward or article-shaping stroke.

It is found desirable in practice to provide means for discharging compressed air, steam or other fluid under pressure into the space between the die members when such members are open in order to remove any scale or other loose matter from between the same. This is accomplished by introducing fluid under pressure into the shaping face of each die member through passages 51 and 52. The passage 51 being disposed in the plate 19 and opening into the conical recess in which the ejector part 27 seats and the passage 52 being provided in the movable die member 14 and opening into the recess in which the ejector part 22 seats. It is thus evident that with this arrangement of the passages 51 and 52 the ejector parts 27 and 22 serve as valves for closing the discharge ends of the respective passages when such parts are seated, as shown in Fig. 8. As the part 22 normally stands in open position relative to the passage 52 the cleaning fluid will be discharged from such passage into the space between the dies all of the time except during the article shaping movement of the die member, while the passage 51, however, is only open for a short period after each shaping operation, or during the period of opening movement of the ejector part 27 by the slide controlling ejector mechanism, the part 27 normally standing in passage closing position due to the action of the springs 28 and 41 thereon. The passages 51 and 52 have connection through tubes or pipes 53 and 54, respectively, with a suitable source or sources of fluid pressure supply.

The operation of my invention is as follows: When the movable parts of the machine are in normal at-rest position the slide 6 stands retracted or at the limit of its rearward stroke and the die-block 2, with the attached die members 12 and 14, stands at the limit of its outward stroke with the stock receiving opening 13^a in the die member 12 in register with the stock feed opening 20 through the shear-plate 19. The movable die member 14 also stands in its retracted position relative to the die member 12 with the gage or ejector part 22 thereof in its forwardly projecting or open position relative to the movable die member, thus permitting a cleaning fluid from the passage 52 to be

discharged into the space between the die members. The operator, having projected the headed end of a stock bar *a* through the openings 20 and 13^a and in contact with the 5 gage or ejector part 22, operates the trip commonly used in connection with this type of machine, but not shown, whereby to cause the crank-shaft 8 to have a single revolution imparted thereto, such crank-shaft automatically 10 stopping at the end of a complete revolution thereof by any suitable means, as is well understood in the art. During a revolution of the crank-shaft, the slides 6 and 10 are moved together and the slide 10 15 first acts to effect a movement of the die-block 2 to the right, or from its normal position to article shaping position, thereby causing a cutting off of the stock section *b* from the bar *a* due to the shearing action of 20 the parts 12 and 19, the movement of the die-block stopping with the section *b* in axial register with the ejector part 27, as shown in Fig. 5. Such movement of the block also places the movable die member 14 in proper 25 position to receive the forward end-thrust of the ram or plunger head 7. When such movement of the die-block has been effected the ram or plunger head 7 will have moved into contact with the rear end of the die 30 member 14 so that such die member will be moved therewith during the remainder of the forward stroke of the slide 6. The movement of the die member 14 toward the stationary member 12 causes the metal in the 35 stock section *b* to be upset and to completely fill the space between the forming faces of the two die members.

Should the section *b* contain slightly more metal than is required to form the intended 40 article, as is preferably and usually the case, the surplus metal flows into a marginal space provided between the two die members and forms what is termed the "flash," such flash or surplus metal being designated 45 *d* in Figs. 6 and 8. On the rear stroke of the slide 6 the movable die 14 moves rearward under the influence of the spring or springs 18, and the ejector part 27 is caused to move rearward to eject the formed article 50 *c* from the die member 12 during the initial portion of the rearward movement of said slide due to the finger 39 on the slide engaging and moving the dog 38 of the ejector mechanism therewith. When the dog 38 has 55 been moved a predetermined distance in this manner it is released from the finger 39 by the tripping action of the stationary boss 40, thus permitting the ejector part 27 and connected operating parts to return to their 60 normal positions under the influence of the springs 28 and 41. When the ejector part 27 is unseated the discharge end of the passage 51 is uncovered and permits fluid under pressure to be discharged into the

space between the die members. When the 65 die member 14 has begun its retracting movement the ejector part 22 will be moved forward by the action of the spring 25 to effect a release of the formed article from said die member. As soon as the die member 14 has 70 returned to its normal position relative to the die member 12 the cam-slide 10 will act on the die-block 2 to effect a retraction thereof to its normal at-rest position. Should the ram 7 be provided with the dog 75 45 the die member 14 will be caused to have a positive inward retracting movement imparted thereto from the ram as it starts on its rearward stroke, the dog being automatically released from engagement with 80 the die member when the ram has moved a short distance.

It is found in practice that the making of each die member 12 and 14 in a single unit instead of in separable halves, as has 85 heretofore been common in machines of this character, makes it possible to forge articles in a much more perfect manner than has heretofore been possible with such machines, and prevents the forming of cross ridges or 90 seams on the article at the points of meeting of the die sections.

It will be understood that while the die member 14 is shown, in the present instance, as being made up of several parts, which are 95 rigidly secured together, the specific construction of such members forms no part of the present invention and has therefore not been described in detail. It will also be understood that the invention is not limited to 100 any specific construction, arrangement or form of parts, except in so far as such limitations are specified in the claims.

Having thus described my invention, what I claim as new, and desire to secure by 105 Letters Patent, is,—

1. In combination, a fixed member, an article ejector carried by said member, and a set of cooperating dies relatively movable toward and away from each other and movable together transversely of said member to place them into and out of operative relation to said ejector.

2. In a mechanism of the class described, a fixed member, an article ejector carried by 115 said member, and a set of dies movable transversely of said member to place the cavity of one die into and out of register with said ejector.

3. In combination, a shear plate having a 120 stock feed opening therein, an ejector movably carried by said plate, and a set of dies movable transversely of said plate and arranged and designed for such movements to have shearing coaction with the plate and 125 to place its article shaping portion in register with said ejector.

4. In combination a shear plate, a plunger

- movable toward and away from said plate, a set of article shaping dies movable transversely of said plate and plunger to place the dies into and out of operative position 5 therebetween, the shaping movements of said dies being in the plane of movement of said plunger and actuated thereby, one of said dies having shearing coaction with said plate when moved transversely thereof into 10 operative position, an article ejecting member projecting through said plate and operable to eject a formed article from the shearing die when the dies have been relatively retracted.
- 15 5. In a mechanism of the class described, a part having a stock feed opening therein, a pair of coöperating dies one having an article shaping opening entirely therethrough and the other having an article shaping 20 cavity in register with said die opening, said dies when in one position of their movements having their article shaping portions in register with said stock feed opening to permit the insertion of a stock piece through 25 said feed and die openings and into the cavity of the other die and a stock gage carried by the die having the cavity and yieldingly movable relatively thereto.
6. In a mechanism of the class described, 30 a pair of coöperating dies one having an article shaping opening entirely therethrough and the other having a part in register with said opening, a combined article ejector and stock gage yieldingly carried by one die in 35 position for a stock piece inserted through the opening of the other die to have stock contact therewith.
7. In a mechanism of the class described, 40 a shear-plate, a set of die members one having shearing coaction with said plate, an ejector part movably carried by said plate, and mechanism automatically operable to move said part to eject a formed article from one of said die members.
- 45 8. In a mechanism of the class described, a pair of relatively movable die members, an element movable to impart article shaping movements to one of said members, and an ejector mechanism having an ejector part 50 movable in the plane of shaping movement of said members and operable by said element during a predetermined portion of its movement to release a formed article from one of said die members.
- 55 9. In a mechanism of the class described, 55 a movable element, a set of die members, a part movable to eject a formed article from one of said die members, a mechanism connecting said element and part for imparting 60 movement from one to the other, said mechanism having a member in releasable engagement with said element, and means for coacting with said mechanism member to release its engagement with said element
- when the element has been moved a predetermined extent, and means yieldingly resisting a movement of said mechanism and part by said element.
10. In a mechanism of the class described, 65 a pair of relatively movable die members, means operable to move said die members together from one position to another transversely of the plane of relative movements thereof, and means operable to relatively move the die members when said members 70 have been moved into one position, said die members each being movable as a complete unit by said first means.
11. In combination, a movable die member, a movable element operable to actuate 80 article shaping movements of said die member, and means operable at a predetermined point in a movement of said element to positively start an upward or retracting movement to said die member and then to 85 release it.
12. In combination, a movable die member, yielding means urging a movement of said die member in one direction, a movable element operable to urge a movement of the 90 die member in the opposite direction, and means automatically operable by said element at a predetermined point in its movement to positively start the retracting movement of said die member and then to release 95 such member.
13. In combination, a movable die member, means yieldingly urging a movement of said die member in one direction, a plunger operable to move said die member in 100 the opposite direction to shape an article, a catch member movable with said plunger and operable to have catch engagement with the die member when at the limit of its article forming stroke whereby an inward retracting movement is imparted to the die member from said plunger when the direction of movement of the plunger is changed after the die moving stroke thereof, and means automatically operable to release 105 said catch and die members at a predetermined point in a movement of said plunger.
14. In combination, a pair of relatively 110 movable die members, means for introducing a fluid under pressure into the space between said members, an element movable during relative movements of said die members, and means operable by said element at a predetermined point in a movement thereof to eject a formed article from one of said 115 die members and to permit a discharge of fluid by said first means.
15. In combination, a set of coöperating 120 dies mounted for relative article shaping movements in one plane and for shearing 125 movements together in a plane which is transverse to the plane of shaping movements of the dies, an article ejecting part

positioned to eject an article from one of said dies when the dies are in one position of their shaping movements, said part having ejecting movements in the plane of shaping movements of said dies, and means operable to periodically impart article ejecting movements to said part.

16. In combination, a movable ejector member, a set of coöperating dies relatively movable in one plane and movable together in a different plane transverse to the plane

of movement of the ejector member to place them into operative article ejecting relation to said ejector.

In testimony whereof, I have hereunto signed my name to this specification in the presence of two subscribing witnesses.

JACOB F. ZWIKER.
